TIPOVER DEVICE

Harry W. Hedburg, Stockton, Calif.

Application May 29, 1948, Serial No. 30,021

3 Claims. (Cl. 193—43)

1

This invention is directed to, and it is an object to provide, a novel tip-over device; the same being operative to facilitate the tipping of an elongated, heavy, initially on-end article onto one longitudinal edge thereof.

While designed primarily for tipping full size commercial ice blocks from an upstanding or on-end position, as in storage, to an on-edge position, for transfer from place to place, the device is not limited to this purpose and may be adapted for use to tip over on-end boxes, crates, cartons, or the like.

A further object of the invention is to provide a tip-over device by means of which an on-end article may be tipped to an on-edge position with a minimum of manual effort, and with safety to the handler of the article; the device reducing accidents, preventing breakage, and saving labor.

The danger in the handling of full size commercial ice blocks, weighing three hundred pounds or more, is great when the tipping of the blocks is done without a mechanical aid; the ever-present wet and slippery floor increasing the hazard. The present device provides an effective mechanical aid, which substantially reduces the danger to person, and the breakage of ice blocks in handling.

An additional object of the invention is to provide a tip-over device which is simple and economical to manufacture, easy to install, and very rugged so as to withstand long and hard usage.

Another object of the invention is to provide a tip-over device which includes, in a channel-like body, a platform to receive the on-end article, an adjacent elevated fulcrum over which the article is tipped, and a carry-off chute which receives the tipped article on its side.

A further object of the invention is to provide a practical and reliable tip-over device, and one which will be exceedingly effective for the purpose for which it is designed.

These objects are accomplished by means of such structure and relative arrangement of parts as will fully appear by a perusal of the following specification and claims.

In the drawings:

Fig. 1 is an enlarged longitudinal sectional elevation of the device.

Fig. 2 is a perspective view of the device.

Fig. 3 is a cross section on line 3—3 of Fig. 2.

Fig. 4 is a view similar to Fig. 3, but shows a modified embodiment of the upper fulcrum.

Fig. 5 is a fragmentary longitudinal section of a modified form of the tip-over assembly, for use—for example—with boxes, crates, or cartons.

2

Referring now more particularly to the characters of reference on the drawings, and particularly at present to Figs. 1—3, the device comprises a heavy-duty, all-metal channel-like body 1, which is elongated, as shown.

The body 1 includes upstanding sides 2 which are parallel throughout the major portion of their extent, and diverge outwardly at the entry end 3 of the body, as wings 4.

Between the sides 2, the body 1 includes a floor or bottom plate 5, which extends substantially full length of said body, with the exception of the wings 4.

The floor or bottom plate 5 is preferably of one piece of sheet metal, and is shaped as follows:

The back end portion of the bottom plate 5 is formed as a platform 6, which is inclined forwardly and downwardly from its rear or free edge; said edge being substantially at the level of the floor 7 on which the device rests. The floor 7 has an opening 8 cut therein to permit of the described forward and downward inclination of said platform 6.

A stop wall 9 projects at an upward and forward incline from the front edge of the platform 6, extending upward above the floor 7. It is preferred that the included angle between the platform 6 and upstanding stop wall 9 be substantially 90°.

Above the floor 7 the bottom plate 5 is offset as a forwardly projecting step 10, which thus forms a transverse fulcrum edge 11 extending from side to side of the body.

From the forward edge of the step 10 the bottom plate 5 extends as an upstanding wall 12, which is rounded forwardly to provide another transverse fulcrum 13; such fulcrum 13 thus being elevated above the fulcrum edge 11, and at an advanced point. From the rounded fulcrum 13 the bottom plate 5 extends forwardly and downwardly, to the front end of the body, as a chute plate 14.

The fulcrum 13 is fitted with a transverse row of upwardly projecting prongs 15, and said prongs are so disposed on the rounded portion of the bottom plate which forms said fulcrum 13 that the upper ends or points of said prongs 15 do not project above the plane of the upper surface of the chute plate 14, for the reason hereinafter described.

In lieu of the transverse row of prongs 15, the fulcrum 13 may be fitted, as shown in Fig. 4, with a transverse saw tooth bar 16, wherein the saw teeth project upwardly, with the points thereof

likewise below the plane of the upper surface of the chute plate 14.

The device is used as follows to tip over an elongated on-end article to an on-edge position, here described—by way of example—as an ice block:

A full size, commercial ice block which weighs three hundred pounds or more is indicated at 17, and such ice block is slid edgewise into the channel-like body 1 until such block rests on the platform 6, being tilted forward somewhat by the inclination of such platform, and then resting against the upstanding stop wall 9.

After the ice block 17 is in this position, as in full lines in Fig. 2, said block is manually tipped, causing it to ride first across the fulcrum edge 11 and then the fulcrum 13 to the position shown in dotted lines in said figure. The fulcrums 11 and 13 both engage the block below center; i. e. at relatively low points. When the ice block 17 reaches the fulcrum engaging position, as in dotted lines in Fig. 2, the weight of said block carries it forward and completes the tipping operation, the block falling onto the chute plate 14 as shown in broken lines in said figure. The prongs 15 or saw tooth bar 16 on the fulcrum 13 prevent any back sliding of the ice block as it tips about the fulcrum 13 onto said chute plate 14.

As soon as the ice block 17 falls on edge on the chute plate 14, it slides forwardly down the same and out of the device onto the floor. This sliding of the ice block on the chute plate 14 is not obstructed by the prongs 15 or saw tooth bar 16, for the reason that the points of the same do not project above the plane of the inclined upper surface of the chute plate 14; i. e. the prongs are below the bottom of the block when it rests on the chute plate.

From the foregoing it will be recognized that very heavy and otherwise hard-to-handle ice blocks or other elongated on-end articles may be tipped on edge easily and without danger to the handler. This is of special advantage in the ice industry, where the accident rate has heretofore been very high among ice-block handlers.

In an adaptation of the invention wherein the prongs 15 or saw tooth bar 16 would produce undesirable perforation of an article being tipped over, the device may be modified, as in Fig. 5.

Here the general assembly remains the same, the lower fulcrum edge being indicated at 18, while the upper and advanced, rounded fulcrum is indicated at 19.

However, the perforating type anti-back-slipping means of Figs. 3 and 4 is substituted by a fulcrum rod 20 fixed to the fulcrum 19; said rod 20 being circular in cross section and welded in place, as shown. Additionally, the chute plate 14

heretofore described is replaced by a roller-type conveyor, indicated generally at 21. This embodiment of the invention is used in exactly the same manner as described above.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent are desired:

1. A tip-over device comprising a unitary channel-shaped member including upstanding sides and a bottom, the lower edges of the sides lying in a horizontal plane, the bottom consisting of a platform extending from adjacent the rear end of the member forwardly and downwardly at an angle to the horizontal plane of the bottom edges of the sides, a stop wall at the forward end of the platform extending upwardly at right angles to the platform, a step projecting forwardly from the upper edge of the stop wall and at right angles thereto, the juncture between the stop wall and step forming a fulcrum, another wall curving upwardly and forwardly from the forward edge of the step, such curved wall forming another fulcrum, and a chute plate extending forwardly and downwardly from the forward edge of the curved wall and terminating in the horizontal plane of the bottom edges of the sides.

2. A device as in claim 1 in which the sides diverge outwardly beyond the rear end of the bottom to form a guide for directing the entry of an object onto the platform.

3. A device as in claim 1 including anti-slip gripping members disposed along the fulcrum point of the curved wall, the outward ends of said member terminating in a horizontal plane below that of the forward edge of said wall.
